CLAIM

The ornamental design for a computer generated image for display panel or screen, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a computer generated image for display panel or screen showing our new design;

FIG. 2 is a front view of a second embodiment thereof;

FIG. 3 is a front view of a third embodiment thereof;

FIG. 4 is a front view of a fourth embodiment thereof; and,

FIG. 5 is a front view of a fifth embodiment thereof.

The dot-dashed lines represent the bounds of the claimed design, while all other broken lines are directed to environment. The dot-dashed lines and broken lines form no part of the claimed design.
